DESIGN FOR A PIN-UP LAMP

John Graham, New York, N. Y.

Application April 10, 1946, Serial No. 128,431

Term of patent 7 years

(Cl. D48—4)

To all whom it may concern:

Be it known that I, John Graham, a citizen of the United States, residing at New York, in the county of New York and State of New York, have invented a new, original, and ornamental Design for Pin-up Lamps, of which the following is a specification, reference being had to the accompanying drawing, forming part thereof.

Fig. 1 is a side elevational view of a pin-up lamp, showing my new design.

Fig. 2 is a front view of Fig. 1.

Fig. 3 is a fragmentary front view taken on the line 3—3 of Fig. 1.

I claim:

The ornamental design for a pin-up lamp, as shown.

JOHN GRAHAM.
